(57) **CLAIM**

We claim the ornamental design for a hose bridge extension, as shown and described.

DESCRIPTION

FIG. 1 is a top-front-left isometric view of the hose bridge extension showing the new design;

FIG. 2 is a top plan view thereof;

FIG. 3 is a left side elevational view thereof, for which the right side elevational view would be identical;

FIG. 4 is a front elevational view thereof, for which the rear elevational view would be identical; and,

FIG. 5 is a bottom plan view thereof.

The broken lines in the figures represent the bounds of the claimed design and form no part of the claimed design.
